WRAPPING MACHINE

Joseph S. Pecker and Henry A. Simpson, Philadelphia, and Abraham S. Kirshner, Llanerch, Pa., assignors to Celanese Corporation of America, a corporation of Delaware

Application June 3, 1943, Serial No. 489,436

8 Claims. (Cl. 93—5)

This invention relates to wrapping machines, and relates more particularly to a machine for applying an outside protective wrapper to yarn packages.

In preparing yarn packages, such as cones of yarn or the like, for storage or shipment, they are usually wrapped in a sheet of paper, treated or untreated, before being placed in suitable containers therefor. Heretofore, the wrapping of the yarn packages was done by hand, a method which obviously was time-consuming and costly.

It is an important object of this invention to provide a machine for automatically and expeditiously applying wrappers to yarn packages.

Another object of this invention is the provision of means for automatically removing the yarn packages from the conveyor after they are wrapped, and for depositing the same in suitable containers.

Other objects of this invention, together with certain details of construction and combinations of parts, will appear from the following detailed description.

According to the present invention, an endless conveyor carries vertical spindles on which are adapted to be placed manually the cones or other yarn packages to be wrapped. The conveyor is driven intermittently and is so timed that the spindles come to a stop directly under the center of a wrapping head where a paper wrapper is to be applied to the yarn package. One or more wrapping heads may be provided, depending upon the desired capacity of the machine. When the conveyor is brought to a stop, with a spindle containing a yarn package under a wrapping head, the spindle and package are caused to be raised by a suitable cam and lever arrangement, whereby the yarn package is lifted into the wrapping head where a sheet of paper is wrapped around the yarn package and the ends of the wrapper are twisted together.

The wrapping head consists of a fixed circular base mounting a series of rollers which are tapered when a cone of yarn is to be wrapped, the taper of the rollers being the same as that of the cone. The rollers rotate continuously at a predetermined speed by means of gears, and the rollers are so mounted in suitable housings that their distance from the center of the wrapping head may be varied. As the yarn package is lifted into the wrapping head, the rollers are spread apart to permit the entry of the yarn package. As the yarn package is raised to a desired position within the wrapping head, the rollers are released so that spring means may

pull the rollers inwardly against the yarn package thereby rotating the same. The wrapping paper, cut to size, is held in a suitable magazine from which it is delivered to the wrapping head through a gap in the circular base thereof at a tangent to the package being wound, the sheet being caught between the yarn package and the rollers as they revolve and is rolled or wrapped around the yarn package. As the wrapped package continues to rotate, twister fingers or plates positioned above and below the rotating package are moved inwardly so that they engage and thereby twist the ends of the paper wrapper. The twister fingers or plates are then removed and at the same time the rollers of the wrapping head swing out to permit the withdrawal from the wrapping head of the wrapped yarn package. The conveyor then moves forward a suitable distance to permit an unwrapped package, 20 or more than one unwrapped package, where a plurality of wrapping heads are employed, to move to a position under the wrapping head or heads. At a predetermined point on the conveyor, suitable means are provided for transferring automatically the wrapped yarn packages from the conveyor to a suitable container.

In the drawings wherein one embodiment of this invention is shown,

Figure 1 is a side elevational view of the yarn package wrapping machine of this invention,

Figure 2 is also a side elevational view of the wrapping machine, on a slightly enlarged scale and partly in section,

Figure 3 is a top plan view of the wrapping head of said machine,

Figure 4 is a vertical sectional view of the wrapping machine taken on line 4—4 in Figure 3,

Figure 5 is a top plan view of the transferring mechanism, partly broken away to show the operating gears,

Figure 6 is a detail view, partly in section, of the package gripping means of the transfer mechanism, and

Figure 7 is a detail view of the tripping mechanism for the package gripping means.

Like reference numerals indicate like parts throughout the several views of the drawings.

Referring now to the drawings for a detailed description of this invention, and specifically to Figures 1 and 2, the reference numeral 11 indicates generally an endless conveyor comprising a plurality of carriages or trucks 12 having wheels or rollers 13 thereon adapted to ride on an endless track 14. Each of the carriages 12 is

provided with a relatively fixed cylindrical bearing 15 in which is slidably carried a sleeve 16. The sleeve is mounted on a spindle 17, the upper end 18 of which is adapted to receive the yarn package 19 to be wrapped, the core of the yarn package sitting firmly on the frusto-conical collar 20. The wrapping machine shown in the drawings is designed to wrap a cone of yarn and this invention will be described in connection therewith. The sleeve 16 is provided with an integral collar 21 carrying a set screw 22 for maintaining said sleeve 16 in position on spindle 17. Each spindle is provided with an integral extension 23, the lower extremity of which has a bifurcation 24 in which a roller 25 is journaled. The conveyor is adapted to be moved by an articulated chain 26 which is intermittently driven by a suitable drive means (not shown).

A cam and lever arrangement generally indicated by reference numeral 27 is provided to lift predetermined spindles carrying yarn packages to be wrapped into wrapping heads, generally indicated by reference numeral 28, spaced above and at suitable intervals along the endless conveyor. In the drawings two such wrapping heads are shown. It will be understood, however, that any number may be positioned along the length of the conveyor, depending upon the desired capacity of the machine.

The conveyor movement is so timed that it is brought to a stop with the spindles directly under the center of the wrapping head. At this point spherical bearing surfaces 29 (carried by each of the spindles) on the spindles directly under the wrapping heads enter between bearing surfaces 31 and 32 on lever 33, and roller 25 contacts bearing surfaces 34 on lever 35. Lever 33 is operatively connected to bell-crank lever 36, to one end 37 of which is pivotally attached a lever 38 and on the other end 39 of which is carried a cam follower 41 cooperating with a cam 42 mounted on the same shaft, hereinafter referred to, as cam 42. A lever 43 is pivotally attached to lever 38 and a lever 44, which is similar to lever 33 and which is provided with bearing surfaces 45 and 46 similar in structure and function to bearing surfaces 31 and 32 on said lever 33, is pivotally attached to lever 43. The lever 35 is operatively connected to a bell-crank lever 47, one end 48 of which carries a cam follower 49 cooperating with the cam 42 and the other end 51 of which is pivotally connected to a lever 52 on which is pivoted a lever 53 pivotally carrying a lever 54 having a bearing surface 55 similar in structure and function to bearing surface 34. Cams 42 and 42' are keyed to shaft 56 driven by any suitable means (not shown). As the shaft 56 and cams 42 and 42' rotate, the cam surfaces acts on rollers 41 and 49 lifting the predetermined spindles, the yarn packages entering the wrapping head. The yarn packages are caused to remain in the wrapping heads long enough to have a wrapper applied thereto. On continuation of the rotation of the cams 42 and 42' the spindles are caused to be lowered by the cam operating through the levers. After the wrapped cones are lowered, the chain 26 moves the endless conveyor forward a distance equal to two spaces to bring unwrapped yarn cones in position under the wrapping heads.

The wrapping heads 28 are carried by brackets 56' attached to portions 57 of the machine framework by means of bolts 58. The brackets 56' are provided at their free ends with bearing members 59 in each of which is journaled a

shaft 61 carrying sprocket wheels adapted to be rotated by means of articulated chain 63 driven by any suitable means not shown. Shafts 61 have attached thereto a gear 64 which is adapted to mesh with and rotate a gear 65 on each of shafts 66 journaled in bearings 67 in web 68 and also in bearings 69 formed in the base 71 of the wrapping head. The shafts 66 also have fixed thereto near their lower extremities thereof gears 72 which mesh with and rotate gears 73 fixed to tubular shafts 74 journaled on bearing points 75 in the extremities of a U-shaped holder 76. Shaft 74 carries thereon tapered rollers 77 and 78. The rotation of gears 72 rotate the tapered rollers continuously at a predetermined speed. Holders 76 together with the tapered rollers carried thereby are mounted on brackets 79 for movement toward and away from the center of the wrapping head. The movement of said tapered rollers is governed by the vertical movement of the spindle carrying the yarn package, the movements being so timed that the rollers are spread apart to allow clearance for the cone coming into wrapping position. When the cone has reached a predetermined position in the wrapping head, the rollers are released, a spring 80 acting on arm 81 of bracket 79 pulling the rollers inwardly against the cone causing the rotation of the same.

The paper wrappers 82 are supplied from a magazine 83 by means of a reciprocating member 84, the paper wrapper being supplied at a tangent to the cone through a gap in the circular base. The paper wrapper is caught between the yarn package and the tapered rollers as they revolve and is rolled or wrapped about the cone. At a suitable time a pair of twister fingers or plates 85 carried on arms 86 integral with collars 87 fixed to shaft 88 are swung in position above and below the wrapped cone engaging and twisting the ends of the wrapper. These twister fingers or plates remain in their inner or operative position only long enough to carry out their function and are immediately swung back to their outermost or inoperative position. At the same time the tapered rollers are swung outwardly to permit the withdrawal of the wrapped yarn package on the spindles 17.

At a convenient point along the conveyor, there is positioned means, generally indicated by reference numeral 89, for transferring the wrapped yarn packages from the conveyor and for placing them into suitable containers 91 on another conveyor generally indicated by reference numeral 92. The transfer mechanism comprises a yoke 93 mounted on a shaft 94 which is adapted to rotate in predetermined time relation with the conveyor 11 of the yarn wrapping machine. The yoke 93 is provided with two transfer heads 95 and 96. In operation, the shaft 94 is elevated to a point where the fingers 97 of the transfer heads are clear of the top of the containers 91 and wrapped yarn package 19. As shown in Figures 1 and 5, when one of the transfer heads is over the conveyor in position to remove therefrom two wrapped yarn packages, it is parallel thereto and at right angles to the yoke 93, while the other transfer head is at 45° to the yoke. When the transfer mechanism is in position shown in Figure 1, the gripping fingers 97 in the transfer head 95 over the conveyor 11 are in extended position, while the gripping fingers on the other transfer head 96 are in contracted or gripping position. Means are provided for operating the gripping fingers in a predetermined manner. This means

comprises a rocker arm 98 pivotally mounted in the yoke 93 and having two bifurcated ends in which are journalled the ends of levers 99. The levers 99 are pivoted at 101 on upright brackets 102. The opposite ends of levers 99 are provided with ball bearing members 103 which are journalled in sockets 104 formed in yoke 105 connecting the two gripping members 106 and 107 of each transfer head.

As the yoke 93 is lowered to pick up the two yarn packages, the rocker arm is actuated by a snap action motivator, generally indicated by reference numeral 108, coming into contact with a vertically adjustable trip rod 109. The tripping of the rocker arm causes the gripping fingers of one set of gripping members to move outwardly and the gripping fingers of the other set of gripping members to move inwardly, the gripping fingers being moved through a rod 109' attached to yoke 105, which rod carries a bearing member indicated by reference numeral 111 formed by discs 112 and 113. The bearing member operates bell-crank brackets 114 to which the gripping fingers 97 are attached.

After the transfer head 95 has gripped the two yarn packages on conveyor 11 and transfer head 96 has released the two wrapped yarn packages in container 91, the transfer heads are raised by shaft 94 and are rotated through an angle of 180° by means of a planetary gear system, generally indicated by reference numeral 115, and connecting rod 116 carried in yoke 93. When the transfer head reaches the position over container 91, it assumes a position which is at right angles to the position now shown in Figure 5 of transfer head 96 whereby the wrapped cones may be placed in unoccupied spaces in the container 91.

It is to be understood that the foregoing detailed description is given merely by way of illustration and that many variations may be made therein without departing from the spirit of my invention.

Having described our invention, what we desire to secure by Letters Patent is:

1. A device for applying wrappers to yarn packages, comprising a wrapping head including spaced rollers for applying the wrapper to the yarn package and means for rotating said rollers at a constant speed, means for intermittently feeding said package to a position in vertical alignment with said wrapping head and means for effecting relative movement between said wrapping head and said package.

2. A device for applying wrappers to frustoconical yarn packages, comprising a wrapping head including spaced, tapered rollers for applying the wrapper to the yarn package and means for rotating said tapered rollers at a constant speed, means for intermittently feeding said package to a position in vertical alignment with said wrapping head and means for effecting relative movement between said wrapping head and said package.

3. A device for applying wrappers to yarn pack-

ages comprising a wrapping head including spaced rollers for applying the wrapper to the yarn package and means for rotating said rollers at a constant speed, means for intermittently feeding said yarn package to a position directly below said wrapping head and means for lifting said package into said wrapping head for contact with said rollers.

4. A device for applying wrappers to yarn packages comprising a wrapping head including spaced, radially movable rollers for applying the wrapper to the yarn package and means for rotating said rollers at a constant speed, means for intermittently feeding said yarn packages to a position directly below said wrapping head and means for lifting said package into said wrapping head for contact with said rollers.

5. A device for applying wrappers to yarn packages comprising a wrapping head including spaced rollers for applying the wrapper to the yarn package, means for rotating said rollers at a constant speed and means for moving said rollers in a radial direction, means for intermittently feeding said yarn package to a position directly below said wrapping head and means for lifting said package into said wrapping head for contact with said rollers.

6. A device for applying wrappers to yarn packages comprising a wrapping head including spaced rollers for applying the wrapper to the yarn package, means for rotating said rollers at a constant speed and means for moving said rollers in a radial direction, means for intermittently feeding said yarn package to a position directly below said wrapping head and cam and lever means for lifting said package into said wrapping head for contact with said rollers.

7. A device for applying wrappers to yarn packages comprising a wrapping head including spaced rollers for applying the wrapper to the yarn package, means for rotating said rollers at a constant speed and means for moving said rollers in a radial direction, means for intermittently feeding a yarn package to a position directly below said wrapping head, cam and lever means for lifting said package into said wrapping head for contact with said rollers and means for feeding a wrapper to said rollers.

8. A device for applying wrappers to yarn packages comprising a wrapping head including spaced rollers for applying the wrapper to the yarn package, means for rotating said rollers at a constant speed and means for moving said rollers in a radial direction, means for intermittently feeding a yarn package to a position directly below said wrapping head, cam and lever means for lifting said package into said wrapping head for contact with said rollers and means for feeding a wrapper to said rollers at a tangent thereto at a point between said rollers.
